UNITED STATES PATENT OFFICE.

HARRIET JOSEPHINE CHAPMAN, OF PASADENA, CALIFORNIA.

FIGURE TOY.

1,169,771.

Specification of Letters Patent.

Patented Feb. 1, 1916.

Application filed January 29, 1915. Serial No. 5,047.

To all whom it may concern:

Be it known that I, HARRIET JOSEPHINE CHAPMAN, a citizen of the United States, residing at Pasadena, in the county of Los Angeles and State of California, have invented certain new and useful Improvements in Figure Toys, of which the following is a specification.

The invention relates to an improvement 10 in jointed toys of the type designed for manual manipulation to cause the toys to assume a variety of postures.

The present invention is directed to a toy and combined supporting and operating 15 member therefor, with the member and toys constructed for a removable interfit to provide for manipulating the toy when desired while yet permitting disassembling of the parts, in a simple expeditious manner to 20 provide for flat storage or packing of the parts for shipment, thereby avoiding the provision of a fixed operating element, as is usually employed in toys of this character.

25 A further object of the invention is the provision of a fastener for securing the jointed parts with relation to each other, the fastener being designed as a simple inexpensive element with which the parts may 30 be readily connected and which will permit the ready renewal of any parts if desired.

The invention in the preferred form of details will be described in the following specification, reference being had particularly to the accompanying drawings, in which:

Figure 1 is a perspective view of the completed toy. Fig. 2 is an elevation of the operating member. Fig. 3 is a section showing the connector joining the jointed sections. Fig. 4 is a perspective view of the connector, the parts being shown separated.

In carrying out the present invention I have shown the improved toys constructed 45 to simulate a boy dressed to represent a plantation darky. The figure includes a body 1 with the head 2 as a fixed part thereof. Arms 3 which are each rigid members are movably connected at 4 to the body. 50 Legs 5 are movably connected to the body at 6, the legs themselves being jointed at 7 representing the knee joint. In connection with the body there is provided an additional element 8, representing in this instance a bandana handkerchief, jointed at 9 55 to the body so as to be capable of independ-

ent movement in the movement of the toy. Of course in connection with other figure representations, such as are contemplated in the present application, the element 8 will 60 represent different forms, in some instances completing the attire, as coat-tails, and said element 8 is contemplated as indicating any and all loose parts which may be applied in this position.

65 As an essential feature of the present invention I provide a handle and operating member in the form of a rod 10 of angular cross section, as shown, and having one end pointed as at 11. The free terminals of the 70 arms 3 are formed with openings 12 of a size to snugly receive and accurately fit the rod 10, so that when the rod is in place it is in effect rigidly connected with the arms so that by taking the ends of the rod between 75 the fingers and rotating the same as desired the movable parts of the toy, beyond the arms are given or permitted such independent action as will cause these parts, and the figure as a whole, to assume various 80 fantastic positions.

In constructing or connecting the jointed sections of the figure it is highly desirable to provide a joining member which is particularly adapted for different functions in that 85 it is capable of convenient application or removal and when in place will permit free movement of the connected sections without binding. To this end I have devised a particular fastener involving two members. 90 The main member 13 involving a shank 14 of an appropriate length and a disk head 15 at one end of the shank. The shank near the opposite end is formed with an annular channel 16 and beyond the channel is rounded as at 17 for convenient insertion. The remaining member of the connector is in the form of a split annular member 18 slightly dished, or concavo-convex, the inner 95 opening corresponding to the diameter of the shank at the annular channel, the split formation permitting the washer to be slipped over the end 17 and snapped into the channel. The member 18 is arranged with the convex portion next the movable 100 member of the toy so as to present as small a contacting surface as possible, thereby avoiding friction.

105 The connector thus described may be readily and quickly applied or removed and when 110 in place permits free and easy movement of the parts with as little friction as possi-

ble and permits such movement without undue wear of the opening in such parts, thereby materially increasing the life of the toy while facilitating its initial assembling or repair.

It is of course to be understood that I contemplate various figure toys, the essential feature of the present invention residing in the means whereby the toys are supported and held for manipulation and the fastener whereby the jointed parts of the toy are connected.

What is claimed is:

1. A jointed figure toy having one or more members thereof formed with a non-circular opening, and an operating member corresponding in size and shape to the opening adapted for removable insertion through the opening to fix said part and member together.

2. The combination with a jointed figure toy having the arms thereof formed with

non-circular openings designed to be alined, and an operating rod having a sectional contour and size corresponding to that of the openings, whereby when the rod is in place in the openings said rod provides a manipulating member for the toy.

3. The combination with a jointed figure toy having the arms thereof formed with non-circular openings designed to be alined, and an operating rod having a sectional contour and size corresponding to that of the openings, whereby when the rod is in place in the openings said rod provides a manipulating member for the toy, one end of the rod being pointed.

In testimony whereof, I affix my signature in presence of two witnesses.

HARRIET JOSEPHINE CHAPMAN.
